UNITED STATES PATENT OFFICE.

ALBERT E. DIXON, OF PROVIDENCE, RHODE ISLAND, ASSIGNOR TO B. A. BALLOU & COMPANY, INCORPORATED, OF PROVIDENCE, RHODE ISLAND, A CORPORATION OF RHODE ISLAND.

DESIGN FOR A HEAD OF CUFF-PINS OR SIMILAR ARTICLES.

No. 40,205.

Specification for Design.

Patented Aug. 10, 1909.

Application filed March 1, 1909. Serial No. 480,796. Term of patent 7 years.

To all whom it may concern:

Be it known that I, ALBERT E. DIXON, a citizen of the United States, residing at Providence, in the county of Providence, in the State of Rhode Island, have invented a new, original, and ornamental Design for Heads of Cuff-Pins or Similar Articles, of which the following is a specification, reference being had to the accompanying draw-

ing, forming part thereof, which shows a perspective view of my said design.

I claim:

The ornamental design for the head of a cuff pin or similar article, as shown.

ALBERT E. DIXON.
